UNITED STATES PATENT OFFICE.

JAMES A. FARLEY, OF GALVESTON, TEXAS.

AUTOMATIC HAMMER.

Application filed June 23, 1925. Serial No. 39,090.

To all whom it may concern:

Be it known that I, JAMES A. FARLEY, a citizen of the United States, residing at Galveston, in the county of Galveston and State 5 of Texas, have invented certain new and useful Improvements in an Automatic Hammer, of which the following is a specification.

This invention relates to improvements in 10 automatic hammers, and has for its principal object to provide one wherein a spool of wire is employed, means being further provided for cutting the wire into predetermined lengths to form nails to be driven 15 into the desired place by the hammer.

A further object of the invention is to 20 provide an automatic hammer wherein means is provided for automatically feeding the wire to the cutting means as well as moving the free end of the wire outwardly 25 from the head of the hammer for a predetermined length.

A further object is to provide an automatic hammer wherein the cutter is of such 25 construction as to bed a piece of wire which has been cut to form a head on the nail whereby the latter may be readily and easily 30 driven home.

A further object of the invention is to 35 provide an automatic hammer of the above mentioned character which will at all times be positive and efficient in its operation, the same being further simple in its construction, inexpensive, strong and durable and further well adapted to the purpose for 40 which it is designed.

Other objects and advantages of the invention will become apparent during the 45 course of the following description taken in connection with the accompanying drawing.

In the accompanying drawing forming a part of this application, and in which like 45 numerals designate like parts throughout the same:

Figure 1 is a side elevation of the automatic hammer embodying my invention.

Figure 2 is an enlarged detail of the head 50 of the hammer with one of the side plates removed showing the position of the parts when the hammer is in an inoperative position.

Figure 3 is an edge elevation showing the 55 plate construction, and the forward end of the cutter, and also the plunger.

Figure 4 is a view similar to Figure 2 showing the position of the parts after a nail has just been cut from the strand of wire and the point thereof is driven into 60 the object.

Figure 5 is a similar view showing the arrangement of the parts when the head of the hammer engages the head of the nail, and the latter is driven home, and 65

Figure 6 is a detail perspective view of the cutter.

In the drawing wherein for the purpose of illustration is shown the preferred embodiment of my invention, the numeral 1 70 designates generally my improved automatic hammer, the head thereof comprising a pair of spaced plates 2 and 3 respectively between which is secured the filler block 4 through the medium of the fastening bolts 5. The 75 handle of the hammer is designated at 6. As is clearly illustrated in Figure 3 of the drawings, the lower ends of the side plates are bent inwardly, and the purpose thereof will hereinafter be more fully described. 80

The end portion of the block 4 is provided with the longitudinally extending cut out portion 7, and the inturned ends 8 of the side plates inclose this cut out portion to provide a pocket for receiving the slidable 85 plunger 9. A coil spring 10 is disposed in the rear end of the pocket and engages the inner end of the plunger, the coil spring normally exerting an outward pressure on the plunger so as to have the forward end of the plunger normally disposed outwardly from the forward end of the head of the hammer. The outward sliding movement of the plunger is limited by reason of the transversely 90 extending pin 11 which is operable in the longitudinally extending cut out portion 12 95 formed in the intermediate portion of the bottom of the plunger.

The block 4 is further provided with the relatively small pocket 13 which is arranged 100 at the side of the pocket in which the plunger 9 is slidable, and arranged in the pocket 13 is the movable jaw 14. A flat spring 15 is also arranged within the pocket 13 and is disposed between the side of the pocket and the inner face of the jaw for normally exerting an outward pressure thereon so that the teeth 16 formed on the outer face of the movable jaw 14 will coact with the oppositely arranged teeth 17 formed in the 105 face of the sliding plunger 9 in gripping and holding the wire 18 from which is to be 110

formed the nails in a manner to be herein-after more fully described.

The wire 18 from which the nails are adapted to be formed is wound on a suitable 5 spool 19, which is rotatably supported on the handle 6 by means of the bracket 20. The wire extends from the spool through the guide eye 21 and over the curved guide member 22 which is secured on the side plate 2, 10 and thence through the opening 23 so that the same will enter the head of the hammer between the coacting faces of the plunger and movable jaw, respectively. The side plate 2 is provided with struck out portions 15 24 so that access to the spring 10 arranged within the rear end of the part 7 may be had.

Slidable in the block 4 between the forward edges of the side plate is the diagonally arranged cutter bar 25. The lower end 20 of the cutter bar is provided with the cutting edge 26, and the forward end of this bar is concaved as illustrated at 27, and the purpose of this particular construction will be presently explained. The lower forward 25 end of the cutter bar is adapted to protrude slightly beyond the forward end of the head of the hammer so that the cutting edge 26 thereof will cooperate with the face of the forward end of the plunger 9. The upper 30 end of the cutter bar extends into the cut out portion 28 provided in the block 4 and a spring element 29 is provided for normally holding the cutter bar in its raised position.

A dog 30 is adapted for slidable movement 35 in the cut out portion 28, the upper end of said dog being provided with a longitudinally extending slot 31 in which operates the pin 32, whereby the sliding movement of the dog is limited. The lower end of the dog is 40 offset to provide the head 33, and the bottom face of the head is inclined, and engages the inclined upper end of the slidable cutter bar 25. A flat spring 34 is arranged in the cut out portion 28, and engages the forward 45 edge of the dog for normally holding the same in the position as shown in Figure 2.

The block 4 is further provided with the curved cut out portion 35, the same communicating at its lower end with the pocket 50 7, and at its upper end with the cut out portion 28. A curved lever 36 is disposed in the curved cut out portion 35 and is pivotally supported adjacent one end therein as at 37. One end of the curved lever 36 engages the 55 upper face of the offset head 33 formed on the lower end of the dog 30, while the other end of the curved lever normally rests in the notch 38 provided therefor in the rear end of the sliding plunger 9. A flat spring 39 is 60 provided for normally holding the curved lever in the position shown in Figure 2.

Normally the parts of the hammer are 65 arranged as shown in Figure 2 of the drawing, and when it is desired to drive a nail into the desired object, a blow is struck by

the forward end of the head of the hammer against the object so as to cause the plunger 9 to move rearwardly in its pocket against the tension of the coil spring 10. As the plunger moves rearwardly in its pocket, the notch 38 being beveled, will cause the other end of the lever 36 to swing simultaneously causing the other end of the cut out lever to exert a downward movement of the offset head 33 of the slidable dog 30, and as a result, the cutter bar 25 will move downwardly so that the cutting edge 26 thereof will cut the wire at a point adjacent the forward end of the head, thus forming a nail; illustrated at 40. This construction is clearly 70 illustrated, as is also the arrangement of the parts during the aforementioned operation, in Figure 4 of the drawings.

Simultaneous with the cutting of the wire to form the nail 40, the cut end of the nail will ride up against the concaved face 27 of the cutter bar so as to form a head 41 on the nail so that the head of the hammer may engage the same and drive the nail into the object as is clearly illustrated in 80 Figure 5.

During the aforementioned operations, the gripping teeth 16 and 17 will engage the portion of the wire which is disposed between the jaw and the sliding plunger, and as soon as the head of the hammer is disengaged from the object in which the nail has been driven, the spring 10 will force the plunger 9 outwardly, simultaneously causing the free end of the wire to move outwardly with the plunger, and again turn the parts to the position shown in Figure 2. In this manner, the hammer is again ready for use.

It will thus be seen from the foregoing description, that an automatic hammer has been provided wherein the parts are so arranged so as to at all times be positive and efficient in carrying out the purposes for which the same are designated.

The simplicity in which my improved automatic hammer is constructed, furthermore enables the several parts to be readily assembled or disassembled and when all the wire has been used, a new spool may be substituted for the old one.

While I have shown the preferred embodiment of my invention, it is to be understood that minor changes in the size, shape and arrangement of parts may be resorted to without departing from the spirit of the invention and the scope of the appended claims.

Having thus described the invention, what I claim as new and desire to secure by Letters Patent is:—

1. An automatic hammer, comprising a head, a handle therefor, a sliding plunger arranged in the head, the forward end thereof projecting beyond the forward end of

- the head, means for feeding the free end of a wire along the side face of the plunger, means for cutting the free end portion of the wire to form a nail, and means for forming a head on the nail. 65
2. An automatic hammer, comprising a head, a handle therefor, a sliding plunger arranged in the head, the forward end thereof projecting beyond the forward end of the head, means for feeding the free end of a wire along the side face of the plunger, means for cutting the free end portion of the wire to form a nail, and means for forming a head on the nail, said means acting during a single stroke of the head of the hammer against the object in which the nail is to be driven. 70
3. An automatic hammer comprising a head, a handle therefor, a sliding plunger arranged in said head, the forward end thereof projecting beyond the forward end of said head, means for feeding the free end portion of a wire along the side face of said plunger, a cutter bar mounted in said head for cutting the wire which projects beyond the head of the hammer to form a nail, and means for actuating said cutter bar. 75
4. An automatic hammer comprising a head, a handle therefor, a sliding plunger arranged in said head, the forward end thereof projecting beyond the forward end of said head, means for feeding the free end portion of a wire along the side face of said plunger, a cutter bar mounted in said head for cutting the wire which projects beyond the head of the hammer to form a nail, and means for actuating said cutter bar, said cutter bar being provided with means for forming a head on the cut end of the nail. 80
5. An automatic hammer comprising a head, a handle therefor, a sliding plunger arranged in said head, the forward end of said plunger projecting beyond the forward end of the head of the hammer, means for feeding the free end portion of a wire along the side face of said plunger, a cutter bar slidably mounted in said head, the lower end thereof being provided with a cutting edge for cooperation with the side face of the projected end of the plunger whereby the free end portion of the wire is cut to form a nail, a dog mounted in the head and engaging the upper end of said cutter bar, and means operable by the rearward sliding movement of the plunger for actuating said dog and said cutter bar, the lower end of the cutter bar being provided with a concaved face on which the cut end of the nail is adapted to ride, thereby forming a head on the nail during a single stroke of the hammer. 85
6. An automatic hammer comprising a head, a handle therefor, a sliding plunger arranged in said head, the forward end of said plunger projecting beyond the forward end of the head of the hammer, means for feeding the free end portion of a wire along the side face of said plunger, a cutter bar slidably mounted in said head, the lower end thereof being provided with a cutting edge for cooperation with the side face of the projected end of the plunger whereby the free end portion of the wire is cut to form a nail, a dog mounted in the head and engaging the upper end of said cutter bar, and means operable by the rearward sliding movement of the plunger for actuating said dog and said cutter bar, the lower end of the cutter bar being provided with a concaved face on which the cut end of the nail is adapted to ride, thereby forming a head on the nail during a single stroke of the hammer, and means for returning the movable elements to their normal position after the head of the hammer is disengaged from the object in which the nail is driven. 90
- In testimony whereof I affix my signature.
- JAMES A. FARLEY.
